UNITED STATES PATENT OFFICE.

GEORGE BURD AND CHARLES BURD, OF DETROIT, MICHIGAN.

AIR-COMPRESSOR PUMP.

1,346,699.

Specification of Letters Patent.

Patented July 13, 1920.

Application filed October 27, 1919. Serial No. 333,631.

To all whom it may concern:

Be it known that we, GEORGE BURD and CHARLES BURD, citizens of the United States, residing at Detroit, in the county of Wayne 5 and State of Michigan, have invented certain new and useful Improvements in Air-Compressor Pumps, of which the following is a specification, reference being had therein to the accompanying drawing.

10 This invention relates to improvements in air compressor pumps, and particularly to improvements upon our air compressor pump of U. S. Patent No. 1,273,728, dated July 23rd, 1918, and is adapted to be used either as a single or double compressor.

15 Among the objects of our invention are:

1. Providing a double walled cylinder in which the space between the walls is subjected to the cooling effect of air drawn into 20 the space by movement of the pistons.

2. Providing an annular double walled cylinder in which the walls are held in working position by a novel cylinder frame carrying the cylinder head, cylinder ring 25 and a packing for the walls of the reciprocating piston.

3. Providing a compressor composed of oppositely extending hollow pistons adapted to enter annular cylinders alternately for 30 compressing the air in first one hollow piston and then the other.

4. Providing an air compressor comprising an annular cylinder and a hollow piston coöperating with the inwardly projecting 35 head of the cylinder for compressing the air, the wall of the cylinder having a thickness less than the width of the annular cylinder in which it enters and the open inner end of the cylinder provided with a packing engaging 40 the interior and exterior of the wall of the hollow piston, whereby friction occurs only at the point of the packing, thus reducing the tendency to heat up, and means whereby the hollow piston is exposed to the air at 5 each stroke to be cooled.

5. Providing a structure in which a hollow open ended piston acts as an air-compressor in conjunction with an annular form of cylinder, the hollow piston telescoping 0 the projecting head of the annular cylinder, thus compressing the air in the hollow piston, whereby a simple construction is provided and one that is capable of easy repair.

Other and more specific objects of the 5 invention will appear from the following description.

In the accompanying drawings—
Figure 1 is a horizontal sectional view of a compressor embodying our invention.

Fig. 2 is an enlarged horizontal sectional view 60 of one of the cylinders showing the supporting frame, piston packing, cylinder head and walls, cylinder ring and the means for holding and adjusting the same in their working position.

We here show our improvement in the form of a double compressor, but our invention is adapted for use in a single acting compressor.

In our invention, A represents an annular 70 cylinder; B represents a hollow annular piston; C represents a cylinder supporting frame, and D represents a driving means for the compressor.

Referring now to the drawings, 1 is the 75 outer annular wall of the annular cylinder A, and 2 is the inner annular wall. 1 and 2 are separate cylindrical members being open at both ends, the outer cylindrical member 1, which forms the outer wall of the compressor pump cylinder, being of a greater cross-section than the inner member 2, and thereby providing a piston receiving space 3.

Upon the outer ends of the members 1 and 2, an annular member 4 is placed which has 85 in its inner side two shoulders 5 and 6, which receive the ends of the members 1 and 2 respectively, and is provided with an opening 7 for the insertion of the hand into the interior of the cylinder A.

A cylinder head a, composed of two plates 8 and 8' is provided with an inlet air-valve 9 to the piston B, and an outlet air valve 10 through which the compressed air is forced through the pipe 11 to a tank (not shown) 95 and rests upon the inner end of the inner wall 2 of the annular cylinder A. The inner plate 8' of the cylinder head a, is provided with a shoulder 12, upon which it rests on the inner end of the inner wall 2, of the cylinder A. A V-shaped groove 13 is formed in the edge of the cylinder head to receive suitable packing 14.

A cylinder ring b, formed of two annular plates 15 and 15' is provided with a shoulder 105 16, upon which it rests upon the inner end of the outer wall 1, of the cylinder A. This ring b has a V-shaped groove 17 in its inner edge in which it carries a suitable packing 18.

Two bolts 19 reach from the outer edge 20 110 of the annular member 4, along the outside of the outer wall 1 of the cylinder A to

the ring *b* and are provided with suitable nuts 21.

Two bolts 22 reach from the inner edge 23 of the annular member 4 to the cylinder head *a* and are provided with suitable nuts 24.

When the nuts 21 and 24 are tightened down, the cylinder frame *c* clamps the cylinder walls 1 and 2 and cylinder head *a* tightly into place and working position. At the same time the packings 14 and 18 are forced toward each other and into the piston space 3.

The piston B is of a cylindrical open ended shape and is constructed to have its walls 25 reciprocate within the space 3, and has a piston head 26 across the center of the piston B, which is held in place by two screw-pintles 27. The wall 25 of the hollow piston B is made thinner than the annular space 3, whereby the piston may move back and forth therein without engaging the walls of the annular cylinder A. As will be readily understood, the piston wall 25 touches only upon the packing 14 and 18, which provides an air-tight fit between the piston wall 25 and the opening 3 of the cylinder A. As will also be understood, the packing can be tightened upon the piston wall 25, by tightening down upon the nuts 21 and 24. Air openings 28, through the annular member 4 into the piston space, 3, provide a cooling means for the piston wall 25. The movement of the piston causes a constant circulation of air in the space 3.

The hollow piston can be reciprocated in any suitable manner. The way shown, however, consists in one end of a pitman or link 29 being swivelly connected to the pintles 27, as at 30. The other end of the links 29 are swiveled at the points 31 to the crank arms 32, which are connected to a suitable crank shaft 33. This crank shaft 33 may be driven in any suitable manner, but, as here shown, it is provided with a gear wheel 34, geared to a wheel 35 carried by a suitable drive shaft 36. This drive shaft 36 may be driven by any form of power (not shown) such as a steam engine, an electric engine or explosive engine.

As in our Patent #1,273,728, thus far we have described only a single compressor embodying our invention, and that may be driven differently from the manner here shown without affecting the invention herein involved. However, our improvement involves providing the piston head with two hollow pistons, which extend in opposite directions and preferably directly in a line with each other and co-operating with an annular cylinder, the same as that heretofore described, and since the hollow pistons and the annular cylinders are exactly alike, it is unnecessary to repeat the description

heretofore given of one compressor, and the same reference letters are applied to both pistons and both cylinders, the improvement being the novel form of cylinder frame for a cylinder composed of two separate open ended cylindrical-shaped members, cooling means for the piston space between the cylinder walls and a two-piece cylinder head and ring, so constructed to receive piston packing that the tightening of the cylinder frame will tighten the packing against the piston wall.

By this construction both the inner and outer walls 1 and 2 of the cylinder A, and the piston wall 28 are subjected to the cooling effect of the surrounding air, and thus materially assist in preventing the overheating of the compressor in operation.

The compressor can be mounted on any suitable base or support, but the means here shown consists of providing the rings 4 and 5 with perforated ears 37, through which bolts may be passed for clamping the compressor to a suitable block or base.

Having thus described our invention, what we claim and desire to secure by Letters Patent is:

1. In an air compressor of the character described, a cylinder comprising separate parallel inner and outer cylindrical walls arranged in separated relation, a separate cylinder head closing one end of the inner cylindrical wall, a clamping ring surrounding the inner end of the outer cylindrical wall and abutting against its inner end, a clamping ring embracing and abutting against the outer ends of both cylindrical walls, bolts connecting both the rings outside of the outer cylindrical wall and connecting the outer ring and the cylinder head and clamping the walls in their operative positions, and a hollow piston operative between said walls, for the purpose described.

2. In an air compressor of the character described, a cylinder comprising separate inner and outer parallel cylindrical walls, arranged in separated relation, a cylinder head provided with inlets and outlets closing one end of the inner cylindrical wall, a clamping ring provided with a shoulder and an outwardly projecting edge embracing the adjacent end of the outer cylindrical wall, a clamping ring provided with inwardly and outwardly projecting edges with intermediate shoulders embracing the opposite ends of both cylindrical walls, clamping bolts connecting the outwardly projecting edges of the rings, clamping bolts embraced within the inner cylindrical wall and connecting the cylinder head and the inner projecting edges of the two shouldered rings, and a piston operative between the cylindrical walls, for the purpose described.

3. In an air compressor, a cylinder comprising separate parallel inner and outer cylindrical walls arranged in separated relation, a split cylinder head provided with 5 inlets and outlets closing one end of the inner cylindrical wall, a split clamping ring provided with a shoulder and an outwardly projecting edge embracing the adjacent end of the outer cylindrical wall, a clamping ring provided with inwardly and outwardly projecting edges with intermediate shoulders and an air opening to the spaced cylindrical walls, embracing the opposite ends of both cylindrical walls, clamping 10 bolts connecting the outwardly projecting edges of the rings, clamping bolts embraced within the inner cylindrical wall connecting the split cylinder head and the inner projecting edge of the two shouldered ring, 15 packing carried by the adjacent split peripheral edges of the cylinder head and the adjacent ring and being forced toward each other when the clamping bolts are tightened, and a hollow piston operative between

the cylindrical walls, for the purpose described. 25

4. An air compressor comprising two oppositely arranged open ended cylinders positioned face to face and each cylinder comprising separate inner and outer parallel 30 walls forming between them a piston space, the inner ends of the inner cylinder walls closed by cylinder heads, each head having air inlets and outlets, a hollow piston consisting of an open ended tube with its 35 opposite ends movable in said piston spaces, a separate piston head within the hollow piston and secured therein intermediate its ends, pintles extending laterally through the hollow piston and within the piston 40 head, and piston operating means connected with the projecting ends of the pintles, the parts operating as described.

In testimony whereof we hereunto affix our signatures.

GEORGE BURD.
CHARLES BURD.
